Term of patent 14 years

(Cl. D26—14)

FIG.1

The broken line fragmentary showing of a telephone handset is for illustrative purposes only.

We claim:

The ornamental design for a telephone hanger bracket, as shown and described.
